ATTORNEY

UNITED STATES PATENT OFFICE

HERMAN NEUWIRTH, OF NEW YORK, N. Y.

DESIGN FOR AN ELECTRIC LAMP FOR FLASH-LIGHT PHOTOGRAPHY OR SIMILAR ARTICLE

Application filed October 31, 1930. Serial No. 37,468. Term of patent 7 years.

To all whom it may concern:

Be it known that HERMAN NEUWIRTH, a citizen of the United States, and resident of New York, in the county of Kings and State of New York, has invented a new, original, and ornamental Design for an Electric Lamp for Flash-Light Photography or Similar Article, of which the following is a specification, reference being had to the accompanying drawing, forming part thereof, in which,

Fig. 1 is a front elevational view of an electric lamp for flash-light photography or similar article, and

Fig. 2 is a side elevational view thereof.

I claim:

The ornamental design for an electric lamp for flash-light photography or similar article as shown.

Dated, New York city, October 27th, 1930.
HERMAN NEUWIRTH.
